DESIGN FOR A FILM PROJECTOR

John N. Loughner and Alfred M. Davock, Detroit, Mich., assignors to Jam Handy Picture Service, Inc., Detroit, Mich., a corporation of Delaware

Application May 13, 1941, Serial No. 100,925

Term of patent 3½ years

To all whom it may concern:

Be it known that we, John N. Loughner and Alfred M. Davock, citizens of the United States of America, residing at Detroit, in the county of Wayne and State of Michigan, have invented a new, original, and ornamental Design for a Film Projector, of which the following is a specification, reference being had therein to the accompanying drawing forming a part thereof, wherein;

Figure 1 is a side elevational view of a film projector, showing our new design;

Figure 2 is a front elevational view of the projector shown in Figure 1; and

Figure 3 is a rear elevational view of the design shown in Figure 1.

The side of the projector opposite to the one illustrated in Figure 1 presents the same appearance as the side shown, and the dotted lines on the sides indicate a decoration.

The dominant features of our design reside in the portions shown in full lines.

We claim:

The ornamental design for a film projector, substantially as shown and described.

JOHN N. LOUGHNER.
ALFRED M. DAVOCK.
